SLICING MACHINE

George W. Shaver and Clarence E. Sibert,
Los Angeles, Calif.

Application June 10, 1936, Serial No. 84,488

1 Claim. (Cl. 146—169)

This invention relates to and has for an object the provision of a novel and highly efficient machine for cutting or slicing various objects and food stuff and more particularly for slicing potatoes, apples and other vegetables and fruits.

An object of the invention is to provide a slicing machine of the character described which will not crush or bruise the potatoes etc. during the slicing operation.

Another object is to provide a machine of the character described in which the friction set up in forcing the potatoes or other objects through the slicer or cutter is reduced to an appreciable minimum whereby to reduce the operating force or manual effort and to make possible a finer cutting and slicing action than heretofore possible with vegetable slicers and the like.

A further object is to provide a cutting or slicing machine having a novel form of cutting or slicer unit made up of an open frame across which thin and narrow blades are stretched and secured under high tension, said blades having sharpened cutting edges and offering a minimum of resistance to the forcing therebetween of the object to be sliced thereby.

Yet another object is to provide a cutting or slicing machine of the character described wherein the cutter or slicer may be comprised of one or more of said slicing units in a novel and efficacious relative arrangement providing for a smooth and uniform slicing of a potato or the like which is forced therethrough the blades of one unit being spaced from the blades of the other unit when more than one of said units is employed whereby one set of blades acts as a guide and support while the other set is slicing.

With the above and other objects in view the invention subsists in the novel construction and combination of parts hereinafter described, illustrated in the accompanying drawing and set forth in the claim hereto appended, it being understood that various changes in form, proportion, size and minor details of construction within the scope of the claim may be resorted to without departing from the spirit or sacrificing any of the advantages of the invention.

Referring to the drawing:

Figure 1 is a side elevation of the slicing machine.

Figure 2 is a sectional view taken on the plane of line 2—2 of Figure 1.

Figure 3 is a "front" end elevation of the machine.

Figure 4 is an elevational view of one of the cutter units.

Figure 5 is an elevational view of another of the cutter units.

Figure 6 is a fragmentary side elevation showing the manner of swaging the ends of the blades in the frame therefor.

Figure 7 is a full size fragmentary sectional view further showing the manner in which the blades are attached to the frame therefor and the relative width of the cutting blades.

The present embodiment of the invention as shown in detail in the accompanying drawing comprises a base 1 on which a frame 2 is mounted, said frame including M-shaped standards 3 joined by rods 4 and supporting a V-shaped guide or trough 5 consisting of spaced bars 6 secured at their ends to the oppositely inclined portions 7 of said standards.

The guide 5 is adapted to guidingly support the potato or other object to be sliced while said potato or other object is forced, by the toothed extruding block 8, thru the slicing means 9 located at one end of the frame. The slot provided by the spacing of the guide bars 6 permits of ready and sanitary cleaning and clearing of the machine after use.

The block 8 is removably secured to a carriage 10 slidable on rods 4, said block having a working fit with the guide 5. As here shown the block is adapted to be manually operated by a lever 11 pivoted at 12 on lugs 13 extending from one of the standards 3, there being a link connection 14 between the carriage 10 and said lever.

It will now be seen that when a potato or other object to be sliced is placed on the guide 5 between the block 8 and slicing means 9, the lever 11 may be readily manipulated to cause the block to force the potato or other object thru said slicing means.

The slicing means as here shown is comprised of separate cutting or slicing units 15 and 16 each of which is identically constructed except that the blades 17 of the unit 15 are disposed to extend angularly across the blades 18 of unit 16 when the two units are employed as shown in Figures 1, 2 and 3. Each unit comprises an open metal frame 19 having the blades extending thereacross in spaced parallel relation to one another and held therein under high tension, say of about 300 pounds. Preferably each blade is seated in "saw" cuts as at 20 in the frame therefor and placed under said high tension then swaged or otherwise secured, thereby to remain under such tension.

It is important to note that said blades are decidedly thin and narrow the thickness thereof

being for example of 28 gauge saw steel while the width thereof is not more than three thirty-seconds of an inch. Such narrow blades will offer a minimum of resistance to the object being forced there-between during the slicing of such object.

When more than one slicing unit is used, say the two units as here shown, the frames are slipped upon the projected ends of the rods 4 10 so that the inner unit frame rests against the adjacent standard 3 and is separated from the other unit by a thin spacer 21. Wing nuts 22 are then turned on the threaded ends of said rods to hold the cutter units assembled.

15 It will be noted that the blades of one unit have sharpened cutting edges that are substantially flush with one side of the frame therefor whereas the blades of the other unit have their sharpened cutting edges reversely arranged, the 20 unsharpened edges thereof being flush with one face of the frame therefor. Thus when the two frames are arranged as here shown; the cutting edges face the object being forced by the block 3 and one set of blades cuts in advance 25 of the blades of the other set, the former acting as supporting guides while the latter cut. Further, the friction caused by cutting two ways simultaneously wherein the "corner" cutting operation is effected by two sets of blades, the cutting 30 edges of which lie in the same plane, is eliminated.

Due to the narrowness and thinness of the blades the forcing of the object thru the cutters or slicers is accompanied by a minimum of friction and it is therefore possible to closely space 35 the blades and provide for a fine slicing action such as desired in making a "shoe string" slice of potato or other object.

Whereas two cutting units are shown, but one 40 may be used if desired and the spacing and relative arrangement of the blades may be varied whereby to produce slices of different shapes and sizes all within the scope of the invention.

It is important to note that the blades of the 45 innermost unit have their cutting edges on a common plane spaced forwardly of the corre-

sponding plane of the cutting edges of the blades of the outer unit, whereby the slicing is done in two planes relatively spaced by the spacers 21. As aforesaid the blades are thin, sharpened and narrow and the unsharpened backs of the blades present very "short" restricted passages thereby reducing friction. In the use of two cutter units the provision of the two planes of cutting action in spaced relation permits the slices, cut by the first set of blades, to expand freely before subjection to the cutting action of the second set of blades; but, at the same time, the first set of blades supportingly guide the material and a smooth and easy cutting action is thereby assured.

15 We claim:

In a slicing machine of the class described, the combination of a fixed, rigid, rectangularly shaped, open frame member provided with slots in one side thereof, means for supporting it at 20 two of its corners, blades secured at their ends across the open space in said frame member in spaced relation to each other and secured in tension in said slots in one side of said frame member so that one side is flush with the side of 25 said frame member forming a cutting member, another similar cutting member with the slotted side adjacent the slotted sides of the first mentioned frame member and arranged with the blades at an angle to the blades in the first mentioned frame member, said blades being sharpened at their receiving edges, a reciprocating block provided with a face portion adapted to fit in the open space in said frames and provided with forwardly extending lugs arranged to fit 30 between the blades in both of said frame members and substantially fill the same, means for guiding said block, consisting of substantially V-shaped guide frame in which said block is reciprocally mounted with one corner downwardly 35 therein, and rods positioned above said guides upon which said block is shiftably mounted for guiding said block in certain relation with said guide members.

GEORGE W. SHAVER.
